UNITED STATES PATENT OFFICE.

WILLIAM F. WILSON, OF DENVER, COLORADO.

COMBINATION HAMMER AND TOOL-HOLDER.

1,258,070.

Specification of Letters Patent.

Patented Mar. 5, 1918.

Application filed February 12, 1917. Serial No. 148,205.

To all whom it may concern:

Be it known that I, WILLIAM F. WILSON, a citizen of the United States, residing at the city and county of Denver and State of Colorado, have invented certain new and useful Improvements in Combination Hammers and Tool-Holders; and I do declare the following to be a full, clear, and exact description of the invention, such as will enable others skilled in the art to which it appertains to make and use the same, reference being had to the accompanying drawings, and to the characters of reference marked thereon, which form a part of this specification.

My invention relates to improvements in tools of the hammer class and of the type requiring a comparatively sharp edge or point arranged at the extremity opposite the hammer or nail driving member. This construction is exceedingly well adapted for use as a brick hammer since tools of this class require a relatively sharp point or edge in order to break the bricks as may be required in cases where a full sized brick is not usable. In order that this work may be done with reasonable accuracy, it is important that the edge of the hammer employed in cutting or breaking the brick, shall be comparatively sharp. Usually a bricklayer will dull the point of his hammer every day thus making it necessary to send the hammer daily to the machine shop for sharpening purposes. My improvement provides for readily removing the cutting tool or blade from the body or holding member of the hammer and the substitution of another tool or blade, thus making it practicable for the mechanic to employ a single hammer body with an indefinite number of tools or blades and making it practicable to send only these blades or points to the shop to be sharpened. Hence where my improvement is used, it is practicable for the workman to have a number of the blades at hand ready for substitution as circumstances may require. This is much cheaper for the workman, and enables him to do much better work since he will always have the advantage of having a sharp blade for use, thus enabling him to do better and more accurate work in cutting the bricks as occasion may require.

It should be explained that my improve-

ment is equally advantageous in the case of picks or other tools which require relatively sharp blades or points. In all such cases the body or hammer head, becomes the holder for the tool, point or blade, the latter being securely held in place through the medium of a relatively stiff leaf spring which normally acts upon the blade to hold it securely in place. This spring, however, may be actuated to cause it to release the blade, by laying the lower surface of the outer end of the blade upon a hard smooth surface, and then rocking the hammer head forwardly, whereby the blade acts as a lever in moving the holding extremity of the spring outwardly, far enough to permit the placing of a pin or nail through the outer extremity of the spring which is provided with an eye for the purpose, the opposite ends of the pin resting upon the outer edges of two side walls with which the holder is provided, the latter being cut away or grooved between these walls to make room for the holding spring and the inner portion of the blade or point. After this is done, the dull blade may be removed and a sharp blade substituted, after which by repeating the operation just described, the outer end of the spring may be actuated to release or loosen the nail or pin, thus making it easily removable, after which the spring acts upon the blade to hold it securely in place. My improvement may also be advantageously used in the case of axes, hatchets, and all similar tools if desired, since in order to employ my improvement it will only be necessary to make a relatively thin flat portion which may be inserted in the holder whereby it is in position to be engaged by the spring of my improvement.

Having briefly outlined my improved construction, I will proceed to describe the same in detail, reference being made to the accompanying drawing, in which is illustrated an embodiment thereof. In this drawing:—

Figure 1 is an elevation of a brick hammer equipped with my improvement, the head and blade of the hammer being shown in central longitudinal section.

Fig. 2 is a similar view of the hammer, shown however, in position to actuate the spring in order to insert a pin or nail for

supporting the spring in position to make the removability of one blade and the substitution of another, practicable.

Fig. 3 is a section taken on the line 3—3

5 Fig. 2.

The same reference characters indicate the same parts in all the views.

Let the numeral 5 designate the head of a brick hammer or other similar tool as 10 heretofore outlined. This head is provided with an opening in which is inserted a handle 6 of the usual type. The nail driving extremity 7 of the hammer or other tool may be of any suitable or ordinary construction. 15 Extending from the eye and on the opposite side of the handle from the head member 7, is the holder member 8 in which is formed a relatively deep groove or cavity 9 on opposite sides of which are walls 10. This 20 groove or cavity is closed at its rear extremity as shown at 12, but open at its opposite extremity as shown at 13. The cavity is of sufficient width to receive the inner extremity or portion 14 of a cutting blade or 25 member 15 having a portion 16 extending beyond the holder member and having a relatively sharp free extremity 17. This blade member 16 is normally held securely in place by means of a relatively stiff leaf 30 spring 18 which is located in the cavity 9, its inner extremity being curved as shown at 19 to engage a pin or abutment 20 whose opposite extremities are anchored in the walls 10 of the holder member. Between 35 the inner and outer extremities of this spring 18, is located a second pin 24 which extends transversely of the cavity 9, its extremities being also anchored or supported on the side walls 10 of the holder member. 40 The outer or forward extremity 21 of the spring is curved to form a partial eye, this extremity being bent outwardly whereby it is adapted to receive a pin or nail 25, when the outer extremity of the spring is forced 45 upwardly in the cavity 9, far enough to permit the insertion of a pin transversely through the eye and allow the opposite extremities of the latter to rest upon the edges 22 of the side walls 10 of the holder. When 50 this is done the forward extremity of the cavity is opened below the corresponding extremity of the spring a sufficient distance to permit the ready removal of a dull blade member 15 and the insertion of a sharp one, 55 whenever occasion for such removal and substitution may exist.

Normally the outer or eye extremity 21 of the spring 18, acts upon the blade member 16 to hold the latter securely in place. 60 When, however, it may be necessary to remove a blade member as when the point 17 of the latter becomes dull, it is only necessary to place the hammer upon a smooth flat surface, and tilt it forwardly by the 65 use of the handle 6 which gives the neces-

sary leverage, the point 17 of the blade member being in engagement with the hard flat surface. This operation which is well illustrated in Fig. 2, forces the outer extremity of the spring 21 far enough upwardly, to 70 permit the insertion of the pin or nail 25, by passing the same transversely through the eye extremity 21 of the spring, or by inserting it in the mouth 23 of the eye 21 which is sufficiently open for the purpose. 75 It is intended that this eye shall be open sufficiently to permit the dropping of the nail or pin thereinto when the outer extremity of the spring is forced outwardly to the position shown in Figs. 2 and 3. This 80 is a quicker method of inserting the pin, than by passing it endwise through the eye, though either method may be employed. It is, however, practicable to leave the eye sufficiently open in the rear to permit the dropping of the pin or nail into place, and at the same time have its free extremity turn into such position that when the pin or nail is in the position shown in Figs. 2 and 3, it will support the spring in position to release the 85 tool. As soon as the spring is in this position, the manner of removing the dull blade member and the substitution of a sharp one will be readily understood. As soon as the sharp one is in place, a slight additional 90 movement of the outer extremity of the spring, in the releasing direction and accomplished in the same manner as heretofore described, will loosen the nail or pin 22 thus permitting its easy removal, after 100 which as soon as the force applied for releasing the nail, ceases to act, the spring 18 will resume its normal position in engagement with the blade member whereby the latter is held securely in place. 105

Having thus described my invention, what I claim is:—

1. A device of the class described including a head having an eye, a handle entering said eye, a socket extending beyond the eye 110 in one direction and having side walls, a leaf spring anchored in said socket, its outer portion being yieldable to facilitate the insertion and removal of a blade, which has a part projecting into the socket and another 115 part extending therefrom, the spring normally engaging the said blade in securing relation, and a pin adapted to engage the outer extremity of the said spring and the side walls of the socket for holding the 120 spring in the open position to relieve the blade of all pressure for the purpose set forth.

2. A device of the class described comprising a head having an eye, a handle inserted 125 therein, the said head having a socket, a blade member having a part arranged in said socket, a spring arranged in the socket and engaging the blade member in securing relation, and means for anchoring the inner 130

extremity of the spring within the said socket, the outer extremity of the said spring being formed to facilitate the insertion of means for supporting said extremity upon the walls of the socket to permit the removal and insertion of a blade member.

3. A device of the class described, including a head having an eye, a handle entering said eye, a socket extending beyond the eye in one direction and having side walls, a leaf spring anchored in said socket, its outer portion being yieldable to facilitate the insertion and removal of a blade, a pin engaging the outer extremity of the spring and the side walls of the socket for holding the spring in the open position and a blade having a part projecting into the socket and another part extending there-

from, the spring normally engaging the blade in securing relation.

4. A device comprising a head having an eye, a handle in said eye, the head having a socket, a blade member having a part extending into said socket, a spring in the socket and engaging the blade member in securing relation, means for anchoring the spring within the socket, and means to engage the outer extremity of the spring and support the same from the walls of the socket to permit insertion and removal of the blade member.

In testimony whereof I affix my signature, in presence of a witness.

WILLIAM F. WILSON.
